PREPARATION OF 5-CYANOTETRAZOLES
 Lucille Theresa Morin and Ken Matsuda, both of Stamford, Conn., assignors to American Cyanamid Company, New York, N.Y., a corporation of Maine
 No Drawing. Filed May 6, 1960, Ser. No. 27,284
 4 Claims. (Cl. 260—308)

The present invention relates to the novel preparation of 5-cyanotetrazole. More particularly, it relates to the synthesis of 5-cyanotetrazole utilizing 1-cyanoformimidic acid hydrazide by the simultaneous nitrosation and ring closing of the same.

It is known that 5-cyanotetrazole can be prepared by reacting hydrazoic acid with cyanogen. The use of such reagents, especially in large scale operations, creates a serious safety hazard problem. There has been a need to provide a process capable of yielding premium grade 5-cyanotetrazole in good yield while lessening the dangers inherent in the prior art reaction.

It is, therefore, a principal object of this invention to provide a novel process for the preparation of 5-cyanotetrazole. It is a further object to provide a process for the preparation of 5-cyanotetrazole which is capable of being carried out in the presence of a relatively stable and safe reactant. It is still a further object to provide a process for the preparation of 5-cyanotetrazole from 1-cyanoformimidic acid hydrazide. Other objects and advantages of the invention will be apparent to those skilled in the art from the consideration of the ensuing disclosure.

To these ends, 1-cyanoformimidic acid hydrazide can be reacted in a straightforward manner by the simultaneous nitrosation and ring closure of the hydrazide reactant. This is surprisingly accomplished by the utilization of alkali nitrite in the presence of nitric acid.

In accordance with the process of this invention, it has been found that 1-cyanoformimidic acid hydrazide is readily ring closed by means of an alkali metal nitrite in the presence of nitric acid and then recovering the thus-formed 1-cyanotetrazole. Advantageously, the ring closure can be effected over a relatively wide range of temperatures generally between -25° C. and $+25^{\circ}$ C., and preferably at between -10° C. and $+10^{\circ}$ C. It has been further found that the amounts of reactants are not critical. The addition of sufficient alkali metal nitrite is the sole prerequisite and, generally, equimolar amounts of the hydrazide reactant and the nitrite are sufficient to effect the desired ring closure and to obtain a premium product in good yields.

It will be noted that the preparation of 5-cyanotetrazole principally involves a sequence of four stages:

First, 1-cyanoformimidic acid hydrazide is dissolved in aqueous nitric acid. Although the amount of nitric acid employed is not critical, sufficient acid should be present to maintain the reactants in solution.

Second, the process involves the addition of a soluble silver salt, such as silver nitrate, to the aforementioned solution of stage 1. Here again, it is preferred to utilize equimolar amounts of silver nitrate and 1-cyanoformimidic acid hydrazide. The addition of the silver nitrate is generally carried out at a temperature between about -25° C. and $+25^{\circ}$ C. At this stage additional nitric acid may be required to maintain the reactants in solution.

Third, an aqueous solution of an alkali metal nitrite is then added to the aforementioned reaction mixture. Insofar as the amount of nitrite is concerned, this too is not critical, except that the minimum amount should be equimolar to the 1-cyanoformimidic acid hydrazide. It is, however, a good practice to slowly add alkali metal nitrite to the reaction in equimolar amounts with re-

2

spect to the hydrazide. Illustrative alkali metal nitrites are sodium nitrite, potassium nitrite and lithium nitrite. At this stage, precipitation is noted. Formation of the silver salt of 5-cyanotetrazole occurs.

Fourth, precipitated silver salt of 5-cyanotetrazole is removed from the reaction medium by conventional means and then washed with water to remove all residual nitric acid. The aqueous menstruum is separated. Additional water is added to the residue. Hydrogen sulfide or an equivalent thereof is bubbled into the aqueous medium. Insoluble silver sulfide is precipitated. Simultaneously, 5-cyanotetrazole is solubilized in the aqueous medium. The latter is separated, for example, by filtration to remove insoluble silver sulfide. The aqueous medium is next evaporated to recover 5-cyanotetrazole.

Thus, the sequence of steps outlined above represents the preferred embodiment of the practice of the invention. However, variations in this sequence are within the purview and contemplation of the invention. Thus, for example, stage 3 which involves the addition of an alkali metal nitrite may be reversed with respect to stage 2 directed to the addition of silver nitrate. Stated otherwise, the addition of an alkali metal nitrite may precede the addition of silver nitrate. Preceding in this alternative manner, ring closure of soluble 5-cyanotetrazole is effected. It has been found, however, that the reaction is less easily controlled and for this reason is not the preferred embodiment of the invention.

The reactant, 1-cyanoformimidic acid hydrazide, is a novel compound and its method of preparation is set forth with particularity in a copending application for Letters Patent, Serial No. 796,202, filed March 6, 1959. In general, the reactant can be prepared by reacting equimolar amounts of cyanogen and hydrazine.

In order to facilitate an understanding of the process of the invention, the following examples are presented. It is, however, understood that these are merely illustrative and are not to be taken as limitative of the invention. All parts and percentages are by weight unless otherwise noted.

EXAMPLE A

Preparation of intermediate reactant.—1-cyanoformimidic acid hydrazide

To a stirred solution of 156 parts of cyanogen in 1000 parts of dioxane at 3° C. to 10° C., there is added over a period of 2.5 hours a solution of 96 parts of hydrazine in 330 parts of a dioxane-methanol (10-1) mixture. Crystallization begins after about one-half hour and the solution gradually turns orange. After the addition of hydrazine is completed, agitation is continued for an additional one-half hour at about 5° C. The product is collected by filtration as 208.3 parts of light orange solid melting at 73° C.— 77° C. It is recrystallized from ethylene dichloride yielding yellow plates, melting at 83° C.— 86° C. Analysis of the 1-cyanoformimidic hydrazide thus prepared is as follows:

Calculated: C, 28.57; H, 4.8; N, 66.64; mol wt. 84.08. Found: C, 29.26; H, 4.94; N, 65.73; mol wt. 86.5.

This intermediate is next cyclized in accordance with the following procedure.

Example 1

2.0 parts of 1-cyanoformimidic acid hydrazide (0.024 mol) as prepared in Example A above are dissolved in 50 parts of water. 20 parts of dilute nitric acid are added to the solution cooled to 5° C. 4.0 parts (0.024 mol) of silver nitrate are then added to the solution which is cooled to about 0° C. An additional 15 parts of concentrated nitric acid are added to the reaction mixture in order to maintain the latter mixture in solution. To the solution 1.7 parts (0.024 mol) of sodium nitrite (dis-

3

solved in 20 parts of water) are then added dropwise with stirring. Cyclization to the tetrazole derivative is rapidly effected, since precipitation is immediately noted. When precipitation terminates on inspection, the reaction mixture is filtered and the precipitant washed with copious amounts of water to remove nitric acid which dissolves therein. Upon filtration, the residual solid silver salt of 5-cyanotetrazole is then added to 100 parts of water. Hydrogen sulfide gas is next passed into the solution to convert the silver salt to soluble 5-cyanotetrazole. Removal of insoluble silver sulfide is effected by filtration. The aqueous filtrate is evaporated to recover one part of 5-cyanotetrazole, a light orange solid. When crystallized from benzene, white crystals are obtained which reddened at 95° C. and decomposed at about 103° C., analyzing as follows:

Calculated: C, 25.27; H, 1.06; N, 73.66; mol wt. 95.05.
Found: C, 25.00; H, 1.27; N, 73.96; mol wt. 94.3.

The product produced by the process of the invention is useful as an insecticide.

Example 2

The utility of 5-cyanotetrazole as an insecticide is presented in the following example:

A solution containing 35% water and 65% acetone is prepared. To 100 parts of the latter solution is added 0.01 part of 5-cyanotetrazole. Nasturtium aphids are mass sprayed with the latter solution and a 100% kill is obtained.

We claim:

1. A process for the preparation of 5-cyanotetrazole which comprises the steps of: reacting 1-cyanoformimidic acid hydrazide with an alkali metal nitrite in the presence of nitric acid and a soluble silver salt to effect nitrosation and cyclization of said hydrazide; and thereafter recovering 5-cyanotetrazole thus-formed.

5 2. A process for the preparation of 5-cyanotetrazole which comprises the steps of: reacting 1-cyanoformimidic acid hydrazide in an aqueous solution containing a mixture of nitric acid and silver nitrate, with aqueous alkali metal nitrite whereby the silver salt of 5-cyanotetrazole precipitates; recovering the said solid silver salt of 5-cyanotetrazole thus-formed; adding water thereto to prepare an aqueous menstruum of the same; passing hydrogen sulfide gas through said aqueous menstruum; concurrently forming silver sulfide precipitate; removing the latter precipitate; and, thereafter, evaporating the residual filtrate containing 5-cyanotetrazole to thereby recover the latter.

10 3. A process according to claim 2 in which the alkali metal nitrite is sodium nitrite.

4. A process according to claim 2 in which the cyclization step is carried out at a temperature of about 5° C.
